UNITED STATES PATENT OFFICE.

WILLIAM McDERMOTT, OF LOUISVILLE, KENTUCKY.

DESIGN FOR A FIRE-PLACE FRONT.

SPECIFICATION forming part of Design No. 20,917, dated July 7, 1891.

Application filed May 6, 1891. Serial No. 391,848. Term of patent 3½ years.

To all whom it may concern:

Be it known that I, WILLIAM McDERMOTT, of Louisville, in the county of Jefferson, in the State of Kentucky, have invented a new and useful Design for Grates, of which the following, taken in connection with the accompanying drawings, is a full, clear, and exact description.

The leading feature of my new design consists in the raised ornamentation for a mantel or grate, consisting of branched work, as shown, on the side panels and projecting ledge of an iron front plate for a parlor grate or mantel, and is shown in the accompanying drawings in Figure 1, while Fig. 2 is added to further illustrate the general appearance of the grate, looking at it from the side before securing it to the wall.

In the annexed drawings, A is a raised bead, while within the bead-line are the two side panels. This ledge B' commences at its upper edge at the surface plane of the front plate in a narrow band e and projects forward and down in an oblique direction to the base-line D, where it terminates. The ledge is connected at its lower corners with the front plate by the brackets C C, which are apparently supporting-brackets, and may be of any approved pattern in detail, substantially as shown.

Rising from the base-line of the ornamental panels B B on both panels I provide the branch work with blossoms, consisting of the stem a and blossoms b, as shown, which extend

nearly or quite to the top of said panels in a serpentine line, becoming less in density as they rise from the base-line. The projecting ledge B' is ornamented by similar stems or branches extending laterally from a point located about central above the fire-place, while at a point slightly removed to the right thereof is the representation of a bird with extended pinions, as in the act of flying. 35

In the lower central part of Fig. 1, within the line formed by the bead F, is an ornamental panel formed in the removable "summer front," this panel representing a hunting scene, wherein the hunter appears with his dog just about to "point" a bird. 45

This design is intended more particularly for cast-metal face-plates for open-grate fire-places, in which case the described ornaments consist, principally, of raised work rising from a mottled, bronze, or other dark background to heighten the desired effect. 50

What I claim is—

The design for a mantel or grate-front, as herein shown and described.

In testimony whereof I have hereunto signed my name, in the presence of two attesting witnesses, at Louisville, in the county of Jefferson, in the State of Kentucky, this 21st day of April, 1891. 60

WILLIAM McDERMOTT.
